UNITED STATES PATENT OFFICE.

LEWIS L. HEPBURN, OF NEW HAVEN, CONNECTICUT, ASSIGNOR TO THE MARLIN FIRE ARMS COMPANY, OF SAME PLACE.

DETACHABLY SECURING BARRELS TO STOCKS.

SPECIFICATION forming part of Letters Patent No. 518,950, dated May 1, 1894.

Application filed March 5, 1894. Serial No. 502,396. (No model.)

To all whom it may concern:

Be it known that I, LEWIS L. HEPBURN, a citizen of the United States, residing at New Haven, in the county of New Haven and State 5 of Connecticut, have invented certain new and useful Improvements in Firearms, of which the following is a specification.

My present invention relates to means for attaching and detaching the barrel of a gun from the receiver or frame, and the invention consists of a cam ring interposed between the receiver and the band or a shoulder on the barrel, by which after the barrel has been screwed fast to the receiver, the parts are 15 cammed or wedged tight, all as hereinafter more fully set forth.

Figure 1 is a side elevation, showing the parts united. Fig. 2 is a top plan view of the same. Fig. 3 is a perspective view of the front end of the receiver; Fig. 4, a perspective view of the rear end of the barrel with the cam ring in position. Fig. 5 is a face view of the cam ring detached; Fig. 6, an edge view of the same; and Fig. 7, a similar 25 edge view looking from the top downward.

The object of this invention is to enable a person to detach the barrel of a gun from its receiver or frame for convenience in packing or carrying the same, and to readily attach the parts when desired for use, and at the same time render the union of the parts rigid and secure. In order to accomplish this result I make the receiver A with a hole, having a screw thread E cut in the wall thereof, as shown in Fig. 3, and on the rear end of the barrel B cut a corresponding thread I as shown in Fig. 4, these parts being fitted so as to be easily screwed together. The barrel is formed with a shoulder against which the 30 stock band H fits snugly as is customary, the rear face of this band being cut away around the barrel and down along one side to make room for the cam ring C and its lever or handle L, as shown in Fig. 4. It is also cut away 35 slightly at its opposite lower side in such manner as to leave a shoulder h against which a projection a on the lower edge of the receiver (shown in Figs. 1 and 3) strikes when the parts are screwed together, the shoulder 40 h and the projection a being so adjusted or

located in relation to each other as to serve as stops to hold the barrel in the exact position required, when screwed into the receiver. It is obvious that these or any similar stops may be located at other points on the abutting faces, and operate the same, but in practice I find this the most convenient arrangement. I then construct a cam-faced ring C, of the form shown in Fig. 5, the hole in said ring being such as to enable it to be slipped 55 over the screw thread on the rear end of the barrel, and fit against the band H as shown in Fig. 4, it turning freely on the barrel, and its handle or lever L fitting in the recess formed by the cut away portion of the band 60 at one side, and projecting at the lower edge far enough to be operated by the hand, as shown in Figs. 1 and 4. One face of this ring C is made inclined or wedge shaped, as shown at b, Figs. 6 and 7, and the face of the band 65 against which it bears is correspondingly inclined transversely as shown in Figs. 1 and 2, so that when the band is turned in the proper direction, these inclined faces bear 70 one against the other, and thus the ring acts 75 as a wedge or cam between the abutting faces of the receiver and the band, thus rendering the union of the barrel and the receiver tight and perfectly rigid. It is obvious that in case no stock band be used, the ring will bear 80 directly against the shoulder on the barrel, and have the same effect; but as most guns, and especially magazine guns are constructed with such a band, I have so shown it.

In order to limit the movement of the ring, 85 I form it with a shoulder d as shown in Fig. 5, which, when the lever or handle is thrown outward to unlock the parts, strikes against a corresponding shoulder on the band as shown in Fig. 4, where the lever is shown 90 thrown outward and the shoulders in contact. It is obvious that the incline may be made on either face of the ring, it only being necessary to locate the incline on the part against which it bears opposite the incline on the 95 ring. The ring is held in place on the barrel by a screw l, Fig. 4, the surface of the ring being cut away so as to permit the edge of the screw head to lap over it and prevent it from falling off, this cut-away portion be- 100

ing of sufficient extent to permit the ring to be moved as far as is necessary.

In case it be desired to apply this invention to a magazine or repeating gun having its magazine tube under and parallel with the barrel, and in which case the follower F which forces the cartridges out of the tube into the receiver would project beyond the face of the band, it will be necessary to withdraw the follower F far enough to have its end flush with the face of the band, or a little more, in order to enable the barrel and receiver to be screwed together or unscrewed. In order to do this, I make the magazine tube with its follower movable longitudinally, so that by moving it in the direction of the muzzle of the gun, the follower is moved back out of the way, to the position shown in Fig. 4. For this purpose I arrange the magazine tube and its spring catch which locks it in position, as shown and described in the Patent No. 469,819, issued to J. M. Marlin, March 1, 1892, or in similar manner by which it is rendered movable as described. In case the cam ring be applied to any other than a magazine gun, as it obviously may be with equal advantage, nothing of this kind will be required, as in such case there will be no follower, and consequently none to project or withdraw.

The operation is simply as follows: The follower having been drawn back (in case one be used) the barrel is screwed into the receiver until the projection a strikes against the shoulder h, at which time the barrel will have been screwed home so as to bring the abutting faces of the band and the receiver in contact, when by pressing the lever L inward, the ring will be turned sufficiently to cause its inclined face b to act as a wedge between the parts, and thus lock the parts tight, and render the joint perfectly rigid. It will readily be seen that when the parts are

screwed together until the abutting faces are brought in contact, there can be but very little if any looseness in the joint, and that consequently only a very slight movement of the ring is necessary to render the joint tight and rigid. In practice I prefer to make the inclines so that it will not be necessary to shove the lever entirely home in order to produce the necessary wedging action, while the parts are new, so that in case the screw threads should be worn by use, such wear can be compensated for by simply pressing the lever a little farther in. 45

To detach the barrel, the follower will first be withdrawn, the lever pushed outward to unlock the parts, when the barrel can be readily unscrewed from the receiver.

The device is simple, cheap to construct, 60 and exceedingly efficient.

Having thus fully described my invention, what I claim is—

1. The combination in a gun, of a barrel having its rear end provided with a screw thread, a receiver provided with a hole having a corresponding screw thread, and a cam ring interposed between the band or shoulder on the barrel for wedging and locking the parts fast and rigid as set forth. 70

2. In combination with the receiver and barrel of a gun, a cam ring provided with an inclined or wedge shaped face and a lever or handle for operating the same, said cam-ring being located between the face of the receiver and the band or shoulder on the barrel, substantially as and for the purpose set forth. 75

In witness whereof I hereunto set my hand in the presence of two witnesses.

LEWIS L. HEPBURN.
